APPARATUS FOR FORMING FUEL CHARGES
FOR INTERNAL COMBUSTION ENGINES

Kenneth M. Cunningham, Decatur, and Antonio Santomartino, Chicago, Ill., assignors to Fuelmaster, Inc., a corporation of Illinois

Application April 9, 1940, Serial No. 328,760

21 Claims. (Cl. 123—133)

This invention relates to apparatus for forming fuel charges for internal combustion engines.

A further object is to provide an apparatus for forming fuel charges for internal combustion engines having means for gasifying volatile liquid fuel such as gasoline and to supply the gasified fuel to a stream of air moving into the engine whereby greatly increased power and a substantial reduction in fuel consumption is effected.

A further object is to provide an apparatus of this character wherein the flow of the gasified fuel is readily and accurately controlled to provide the necessary engine speed and power.

A further object is to provide a novel apparatus of the character referred to wherein the flow of gasified fuel into the intake manifold is controlled by the throttle through a suitable control valve mechanism, and wherein the supplying of the fuel to such valve mechanism is controlled automatically by a pressure control valve so as to render a supply of gasified fuel constantly available under uniform pressure conditions to the control valve mechanism.

Other objects and advantages of the invention will become apparent during the course of the following description.

In the drawings we have shown two embodiments of the invention. In this showing:

Figure 1 is a vertical sectional view through the apparatus showing its connection with the intake manifold of an internal combustion engine, parts being broken away and parts being shown in elevation.

Figure 2 is an enlarged fragmentary vertical sectional view showing the fuel supply control valve system.

Figure 3 is an enlarged detail sectional view of the pressure control valve taken on line 3—3 of Figure 1.

Figure 4 is a vertical sectional view through a portion of a modified form of the device showing the fuel gasifying means, parts being shown in elevation.

Figure 5 is a side elevation of the same.

Figure 6 is a vertical sectional view on line 6—6 of Figure 4.

Figure 7 is an enlarged vertical sectional view on line 7—7 of Figure 4, and.

Figure 8 is a detail sectional view on line 8—8 of Figure 7.

Referring to Figure 1, the numeral 10 designates a conventional carburetor, the air inlet of which is provided with an air cleaner 11. The carburetor has been only generally indicated in

Figure 1 since it forms no part per se of the present invention. The carburetor is provided with the usual choke 12, and fuel is supplied to the carburetor by a pipe 13. This pipe is adapted to be connected by a three-way valve 14 to a main supply pipe 15 leading from the fuel pump of the motor vehicle or any other source of fuel supply. The valve 14 may be operated in any suitable manner and in Figure 1 it has been shown as being provided with a manually operable arm 16 movable by a rod, Bowden wire or the like 17. The third connection of the valve 14 leads to a pipe 18 for a purpose to be described. The air inlet of the carburetor is flanged as at 19 and such flange is usually connected to a flange 20 carried by the upper end of a pipe 21 secured to the intake manifold 22, it being apparent that the device as shown in Figure 1 is thus connected to a down-draft fuel supply device. A portion of the present mechanism to be described is introduced between the flanges 19 and 20. The pipe 21 is provided with the usual throttle 23 suitably operated in any desired manner.

The apparatus forming the subject matter of the present invention comprises a fuel gasifier indicated as a whole by the numeral 24. The gasifier comprises an outer shell 25 and an inner shell 26 spaced from the outer shell preferably at least at its bottom and around its sides. A pipe 27 is connected to the exhaust manifold (not shown) of the engine to supply hot exhaust gases to the heating space 29 between the inner and outer shells 25 and 26. Adjacent the upper end of the shell 25 a pipe 30 is connected into the shell 25 to communicate with the heating chamber 29, the pipe 30 leading to a muffler 31 or to any other means for disposing of the exhaust gases.

The pipe 18 leads to a float chamber 32 having a float 33 therein controlling a conventional needle valve 34. The float chamber 32 communicates with the interior of the shell 26 through a pipe 35. It will be obvious that the float 33 operates to maintain liquid fuel at a constant level in the shell 26, for example, at the level shown in Figure 1 and indicated by the numeral 36. The float chamber is provided with a top 37 which must be sealed to the atmosphere in view of the generation of pressure in the shell 26 as will be described.

Referring to Figures 1, 2 and 3, it will be noted that the principal operating parts of the mechanism are associated with a cast body indicated as a whole by the numeral 38. One end of the

body 38 is provided with a passage 39 extending through a downturned end 40 on the body 38 and communicating with the interior of the shell 26 to receive gasified fuel therefrom. A small pipe 41 is connected between the passage 39 and the top of the float chamber 32 to equalize pressures in the float chamber without a surging of the fuel through the pipe 35, thus steady-ing the action of the float 33.

Gas passing from the gas generator through the passage 39 is controlled by a pressure regulator indicated as a whole by the numeral 42. This regulator may be any desired form of regulator, and one form of such device has been shown in Figures 1 and 3. The passage 39 com-municates with a chamber 43 closed at its top by a diaphragm 44 secured in position by a hollow plug 45 having an upwardly extending internally threaded collar 46. A compression spring 47 urges the diaphragm 44 downwardly and has its upper end seated within a hollow cap 48 threaded in the collar 46.

In axial alignment with the chamber 43 the body 38 is provided with a vertical passage 49 the lower end of which forms a valve seat for a purpose to be described. The passage 49 com-municates at its upper end with a passage 50 as shown in Figures 1 and 3. A valve 51 is adapt-ed to close the lower end of the passage 49 and is urged upwardly by a spring 52 having its lower end seated in a cap 53. The valve 51 is provided with a depending stem 54 slidable in a guide 55 formed in the cap 53. Gas flows downwardly from the chamber 43 through passages 56 on op-posite sides of the portion of the body 38 in which the passages 49 and 50 are arranged, as shown in Figure 3, the gas flowing from the spaces 56 into the passage 49 under the control of the valve 51. A disk 57 is connected to the diaphragm 44 and is provided with depending arms 58 extending downwardly through the spaces or passages 56 to engage the valve 51. The springs 47 and 52 oppose each other and the spring 57 normally retains the valve 51 in slightly open position, the position of the valve depending upon the pressure in the chamber 43, as will become apparent.

The passage 50 supplies gas from the pres-
sure regulator valve to a fuel regulator carried by the body 38 and indicated as a whole by the numeral 59. The fuel regulator is shown in de-tail in Figure 2 and reference is made to such figure. The passage 50 leads to a relatively large chamber 60 closed at its top by a diaphragm 61 above which is a chamber 62 formed by the diaphragm 61 and by a wall 63 integral with a preferably cast body 64. The diaphragm 61 carries a valve stem 65 having a valve 66 at its lower end engageable with a valve seat 67 formed at the upper end of a fuel passage 68. The pas-sage 68 communicates with a fuel outlet cham-ber 69 formed in the body 38.

Pressure in the chamber 60 influences the posi-tion of the diaphragm 61 and hence the valve 66, and this pressure is communicated to the chamber 62 through a bleed orifice 70 formed in the stem 65. A leaf spring 71 is carried by the stem 65 and engages the wall 63 to tend to urge the valve 66 toward closed position.

Above the wall 63 a chamber 72 is formed in the body 64 and is closed at its top by a dia-phragm 73 secured in position by a cap 74. The diaphragm 73 is provided with a stem 75 to which is rigidly connected a resilient arm 76 adapted to fulcrum on a knife edge 77 integral 75

with and projecting upwardly from the wall 63. The arm 76 carries a depending stem 78 the lower end of which is formed as a conical valve 79 engaging a seat 80 formed at the upper end of a port 81 which is adapted to establish com-munication between the chambers 62 and 72.

The cap 74 is provided with a chamber 82 therebeneath and the pressures in this chamber and the chamber 72 control the position of the diaphragm 73. The cap 74 is provided with a port 83 from which a pipe 84 (Figure 1) leads to the intake pipe of the carburetor. Pressure variations in the latter pipe incident to resist-
10 ance to air passing through the air cleaner 11 will be duplicated in the chamber 82, as will be apparent.

The main body 38 and body 64, and cap 15 74 are provided with a passage 85 the lower end of which communicates with the chamber 69. A port 86 in the body 64 communicates between the chamber 72 and the passage 85. The upper end of the passage 85 is adapted to communicate with a port 87 under the control of a manually adjustable valve 88. The port 87 is connected to one end of an idler tube 89, the other end of which communicates as at 90 (Figure 1) with the pipe 21 adjacent the throttle 23 to be in-fluenced by vacuum in the intake manifold when the throttle is in idling position.

As previously stated, the flanges 19 and 20 (Figure 1) are conventionally secured together. With the use of the present construction, how-ever, these flanges are separated and one end of the body 38 is inserted between and secured to these flanges. Such end of the body 38 is provided with a passage 91 therethrough forming a direct connection between the pipe 21 and the intake pipe of the carburetor. This passage communicates with a chamber 92 adjacent the chamber 69 and separated therefrom by a wall 93. This wall is provided with an opening 94 controlled by a manually adjustable fuel load control valve 95.

A somewhat different form of the invention is shown in Figures 4 to 8 inclusive, the differ-
45 ence lying particularly in the gas generating apparatus. In the form of the invention previously described, the mechanism is provided with a gas generator adapted to be connected to a conven-tional exhaust manifold. In the form of the invention shown in Figures 4 to 8 inclusive, a special exhaust manifold is employed with the gas generator built therewith as an integral part thereof. Referring to Figures 4 to 7 inclusive the numeral 96 designates a preferably cast body as a whole, the lower portion of which is elon-gated horizontally as at 97 to form a heating chamber 98 which forms the exhaust manifold for the internal combustion engine, this cham-
50 ber being adapted for connection through open-
55 ings 99 with the exhaust ports of the engine. One end of the chamber 98 communicates with a preferably integral outlet pipe 100 which is adapted for connection with the usual muffler (not shown).

70 A chamber 101 is arranged within and spaced from all sides of the casing 97. The chamber 101 is preferably formed integral with the cas-ing 97 being spaced from and supported with respect to the casing 97 by integrally cast connect-ing bars 102. The chamber 101 generally follows the shape of the casing 97 except that the chamber 101 is provided with downward ex-tensions 103 between adjacent pairs of inlet opennings 99, and a similar downward extension

104 between the central pair of inlet openings 99, the embodiment of the invention shown being for a six cylinder motor. The chamber 101 is provided with internal integral radiating fins 105 to assist in transferring heat from the exhaust chamber 98 to the interior of the chamber 101. The outer face of the casing 97 is preferably open and provided with a closure plate 106, as shown in Figures 6 and 7.

Referring to Figures 5 and 6 the numeral 107 designates a pipe extending horizontally adjacent and parallel to the cover plate 106. This pipe turns inwardly at its ends as at 108 for connection with nozzles extending into the interior of the chamber 101 adjacent the ends thereof, the approximate positions of these nozzles being indicated by the dotted lines in Figure 4. The nozzles 109 are adapted to inject liquid fuel in spray form into the interior of the chamber 101 to be converted into gas therein by the heat of the exhaust gases in the chamber 98. Fuel is supplied to the pipe 107 by a pipe 110 connected thereto by a T 111 (Figure 5).

The form of the invention shown in Figures 4 to 8 inclusive also contemplates the use of a conventional carburetor, to be referred to later, for supplying explosive mixture to the engine until sufficient heat has been generated in the exhaust manifold to gasify fuel within the chamber 101. A pressure or thermostatically controlled valve mechanism has been illustrated diagrammatically in Figures 5 and 7 and indicated by the numeral 112. This valve is controlled by an element 113 extending through the adjacent portion of the exhaust chamber 98 and terminating in a pressure or thermostatically responsive member 114 arranged within the chamber 101. Fuel is supplied to the valve mechanism 112 through a pipe 115 leading from the fuel pump to the valve mechanism, adapted to connect the pipes 110 and 115 when the gas generator is operating after the motor has been running a sufficient length of time. The pipe 115 is preferably provided with a check valve 115' for a purpose to be described. During initial operation of the engine, the valve mechanism 112 connects the pipe 115 to a fuel pipe 116 leading to the conventional carburetor to be referred to.

It has been found that improved results may be obtained by supplying water in atomized form to the heating chamber 101. To this end, water is supplied through a pipe 117 by any suitable form of pump indicated diagrammatically by the numeral 118. From the outlet side of the pump a pipe 119 extends to the cover 106 (Figure 7) for connection with a spray nozzle 120 extending into the heating chamber 101. This nozzle is preferably connected into the heating chamber 101 centrally of the length thereof and preferably near the bottom of the depending portion 104 of the heating chamber as shown in dotted lines in Figure 4.

The heating chamber 101 is provided in its top and substantially centrally of the length thereof with an outlet duct 121 (Figures 4 and 7) from which gas generated in the chamber 101 is supplied to a pressure regulating valve mechanism indicated as a whole by the numeral 122 and similar to the valve mechanism 42 previously described. The duct 121 communicates with a chamber 123 formed in the body 96 and closed by a diaphragm 124 held in position by a hollow plug 125 threaded into the body 96. A compressing spring 126 urges the diaphragm 124 to the left as viewed in Figure 7, and the outer end

of this spring seats in the end of a threaded plug 127, this plug obviously being adjustable to adjust the tension of the spring 126.

In axial alignment with the chamber 123, the body 96 is provided with a passage 128 communicating with a vertical passage 129. The end of the passage 128 forms a valve seat controllable by a valve 130 urged toward closed position by a spring 131 seating in a threaded cap 132. The portion of the body 96 in which the passage 128 is formed is provided on opposite sides with spaces 133 (Figure 8) in direct communication with the chamber 123 and communicating through the inner end of the plug 132 with the space to the left of the end of the passage 128 as viewed in Figures 7 and 8. Thus when the valve 130 is open, gas flows from the chamber 123 through the spaces 133 and thence into the passages 128 and 129. The diaphragm 124 is provided with a central disk 135 having parallel arms 136 extending through the spaces 133 to engage the valve 130 to exert the force of the spring 126 thereagainst. The pressure of the spring 126 normally slightly overbalances the pressure of the spring 131, and upon an increase in pressure in the chamber 123, the pressure moves the diaphragm 124 toward the right as viewed in Figures 7 and 8 to permit the spring 131 to move the valve 130 toward its closed position. Conversely, a drop in pressure in the chamber 123 permits the spring 126 to move the valve 130 away from closed position, thus controlling the supply of gas to the passage 128.

The passage 129 communicates with a chamber 137 formed in the body 96 and closed at one side by a diaphragm 138. This diaphragm carries a stem 139 to which is connected a valve 140 engageable with a port 141 to control the passage of gas therethrough. The body 96 is provided with a horizontally projecting hollow portion 142 divided by a wall 143 to form chambers 144 and 145, the valve 140 controlling the passage of gas from the chamber 137 to the chamber 144. The projection 142 has the chamber 145 thereof communicating with a passage 146 extending through the projection 142. It will be noted that the projection 142 is arranged between and secured to upper and lower sections 147 and 148 of a conventional carburetor, the device being mounted in the same manner as in the form of the invention shown in Figure 1. The upper end 147 of the carburetor is provided with the usual air cleaner 148', while the conventional choke valve 149 and throttle valve 150 are arranged in the respective carburetor sections 147 and 148. The flow of gas from the chamber 144 into the carburetor and thus into the intake manifold is controlled by a fuel adjusting valve 151 adjustable with respect to an opening 152 formed in the wall 143.

A preferably cast body 153 is secured against the diaphragm 138 and has a chamber 154 formed therein facing toward the diaphragm. The body 153 has the chamber thereof formed by a wall 155 and a leaf spring 156 seats against this wall and urges the diaphragm 138 and valve 140 toward the left as viewed in Figure 7. The stem 139 of the valve 140 is provided with a bleed passage 157 affording restricted communication between the chambers 137 and 154, this passage corresponding to the passage 70 shown in Figure 2.

The wall 155 divides the chamber 154 from another chamber 158 formed in the body 153 and the wall 155 is provided with a restricted

passage 159 adapted to afford communication between the chambers 154 and 158. The chamber 158 is covered by a diaphragm 159' carrying a stem 160 to one end of which is connected a spring arm 161. This arm fulcrums on a projection 162 formed integral with the wall 155 and the other end of the arm 161 carries a small tapered valve 163 controlling the passage 159.

At their upper ends, the bodies 96 and 153 are provided with a passage 170 one end of which communicates with the chamber 158 and the other end of which communicates with the chamber 144. A passage 171 communicates between the passage 170 and a pipe 172, the other end of which leads to the carburetor intake pipe 148 adjacent the throttle valve 150. Communication between the passage 171 and pipe 172 is controlled by an idling adjustment valve 173'.

A cap 173 is secured to the diaphragm 159' and is recessed to form a chamber 174 from which a pipe 175 extends to the carburetor pipe 147 (Figures 4 and 5) adjacent the air cleaner 148'. As is true of the chamber 82 (Figure 2) therefore the chamber 174 is subjected to atmospheric pressure except for variations occurring in the carburetor pipe 147 incident to resistance to the flow of air into the carburetor through the air cleaner.

The operation of the form of the invention shown in Figures 1, 2 and 3 is as follows:

The present apparatus, as distinguished from a conventional carburetor does not atomize the fuel to be evaporated by the air passing through the carburetor into the intake manifold, but on the contrary, converts the liquid fuel into gaseous form prior to the mixing of the fuel with the air. Of course, the apparatus is particularly intended for use with internal combustion engines employing lighter fuels such as gasoline.

Gasification of the liquid fuel takes place in the heating chamber 26 due to the high temperature provided in such chamber by the exhaust gases passing through the space 29. It will be apparent therefore, that the proper operation of the apparatus depends upon the heating of the chamber 26, and for this reason a conventional carburetor is employed for the starting of the engine and for the running of the engine until the chamber 26 is heated to the point necessary for the gasification of the fuel.

In starting the engine, the valve handle 16 (Figure 1) is swung to the position wherein the pipe 15 will communicate with the pipe 13 to supply fuel to the carburetor 10. The engine is started in the usual manner and carbureted air will pass to the intake manifold of the engine in the usual manner. The level of the fuel in the float chamber (not shown) of the carburetor will be controlled by the conventional float and the engine will function in accordance with the usual practice.

After the engine has been running a sufficient length of time to heat the chamber 26 to the proper point, the valve handle 16 will be manually operated to disconnect the pipe 15 from the pipe 13 and connect the pipe 15 to the pipe 18. Fuel thus will flow into the float chamber 32, and thence through the pipe 35 into the heating chamber 26 where it will be immediately gasified to be supplied to the engine. In this connection it will be noted that while the three-way valve disconnects the conventional carburetor from the source of fuel supply prior to the running of the engine on gas from the chamber 26, the quantity of fuel maintained in the conventional car-

buretor float chamber will be substantially more than is necessary to continue the operation of the engine until gas is supplied to the engine from the chamber 26.

5 The float 32 controls the height of the liquid approximately at the level indicated by the numeral 36, and the chamber 26 and other elements which are subjected to the maximum gas pressure are constructed to withstand the greatest 10 pressures to which the apparatus will be subjected. The conversion of the liquid fuel into gas will, of course, depend not only on the heat generated in the chamber 26 but also on the pressure present therein. For the heat generated, 15 the pressure within the chamber 26 will rise to the point where there will be no further gasification of fuel except as the fuel is consumed by the engine and when such point is reached, the rate of gasification will exactly correspond to the rate of fuel consumption by the engine.

20 The gas will flow from the chamber 26 through the passage 39 and thence into the chamber 43 of the pressure control valve. Referring to Figure 3, it will be noted that the gas will flow from the chamber 43 downwardly through the spaces 56, thence into the upper end of the cap 53 and upwardly into the passage 49 to flow therefrom through the passage 50. The valve mechanism 42 functions in the same manner as any standard pressure control valve mechanism. It will be apparent that relatively low pressures will be present in the chamber 43 when gasification of the fuel commences, in which case the spring 47 will urge the valve 51 downwardly to open it 25 to a degree proportional to the pressure present in the chamber 43. As the pressure builds up in the chamber 43, the diaphragm 44 will be forced upwardly against the tension of the spring 47 to move the valve 51 closer to the end of the passage 49, thus retarding the flow of gas into such passage as the pressure of the gas increases in the chamber 43.

30 Thus gas will be supplied at a constant pressure to the control chamber 60 (Figure 2). When 45 the engine is not running, the bleed passage 70 equalizes pressure in the chambers 60 and 62 and the spring 71 holds the valve 66 in closed position. During the running of the engine, partial vacuum in the intake manifold will be 50 communicated to the chamber 69 (Figure 2) thence through passage 85 and port 86 to the chamber 72. Pressure above the diaphragm 73 will then hold this diaphragm in a depressed or lowered position, thus opening the valve 78 to an 55 extent commensurate with the partial vacuum present in the chamber 72. As the pressure drops in the chamber 72, the valve 79 will be opened to provide a greater degree of communication between the chambers 62 and 72 than is 60 provided between the chambers 60 and 62 through the bleed passage 70, and under such conditions the diaphragm 61 will be moved upwardly to open the valve 66 and admit fluid from the chamber 60 to the chamber 69 and thence through 65 the opening 94 (Figure 1) into the intake manifold. It will be obvious that the extent to which the valve 66 opens will depend upon the degree to which pressure drops in the chamber 72 to move the diaphragm 73 downwardly and thus 70 open the valve 79. Some fuel, of course, will flow through the passages 10 and 81 (Figure 2) into the chamber 72 and thence through passages 86 and 85 and chamber 69 and opening 94 to be supplied to the intake manifold.

75 The degree of vacuum in the intake manifold

is dependent not only on the rate of piston displacement but also upon resistance offered by the air cleaner 11 to the entrance of air into the carburetor. Since this is true, it is desirable that the chamber 82 (Figure 2) be not connected directly to the atmosphere. On the contrary, the proper functioning of the diaphragm 73 is better secured by also rendering the pressure in the chamber 82 subject to the resistance of the air cleaner 11. For this reason the pipe 84 is connected between the chamber 82 and the carburetor intake adjacent the air cleaner 11.

The pressure above the throttle valve 23 is relatively high when the throttle is in the idling position due to the resistance offered by such valve to the entrance of air into the intake manifold. Under such conditions the degree of vacuum affecting the diaphragm 73 through the chamber 89, passage 85 and port 86 would be too low to hold the valve 66 in more than a very slightly open position. For this reason the idler pipe 89 is employed. This pipe has one end connected to the intake pipe adjacent the throttle 23 and accordingly is subjected to a relatively great degree of partial vacuum when the throttle is in idling position.

Under such conditions, a partial vacuum will be established beneath the diaphragm 73 through the pipe 89, passages 87 and 85 and port 86, the degree of communication between the passages 85 and 87 being controlled by the manually adjustable valve 88. As previously stated, there will not be a great drop in pressure in the chamber 68 when the throttle is in idling position, the degree of vacuum not being nearly as great as it is in the pipe 89. Hence the valve 88 is adjusted to control the rate of exhaustion of air from the passage 85 into the pipe 89 to provide the desired degree of partial vacuum in the chamber 72 to open the valve 79 sufficiently to draw gaseous fuel through the passage 70 (Figure 2), chamber 62, passage 81 and into the chamber 72, from which the gas flows through port 86, passages 85 and 87 and idler pipe 89 into the intake manifold. The partial vacuum thus created in the chamber 72 also results in lowering the pressure in the chamber 62 whereby pressure in the chamber 60 will move the diaphragm 61 upwardly and thus open the valve 66 to a greater extent than would occur if the idling pipe 89 were not used. Accordingly some of the idling fuel is supplied through the port 68.

It will be apparent that the present device need not and preferably does not employ any means for heating the air passing into the intake pipe of the carburetor. In a conventional carburetor gasification of the fuel is dependent upon evaporation of the atomized fuel in the short space of time required for the fuel and air to pass from the carburetor through the intake manifold and into the engine cylinders. In the present device, the fuel is converted into gaseous form prior to its mixture with the air which supports combustion of the fuel, and accordingly evaporation of the fuel is not depended upon for gasification of the fuel.

The result is that the relatively cool fuel mixture satisfies the volumetric requirements of the engine cylinders which is not true when and if the mixture is heated and expanded, as is well known. Accordingly maximum power is secured from each power stroke of each piston of the motor. Moreover, complete gasification and complete mixture of the fuel and air occurs before the fuel reaches the cylinders of the engine.

with the result that more complete combustion of the fuel takes place in the engine. The fact that complete combustion takes place within the engine cylinders is quite obvious from the fact that when the exhaust manifold has been removed during tests, very little yellow flame has been projected from the exhaust outlets as compared with the flames projected from the exhaust openings when a conventional carburetor is employed. Actual tests with the apparatus in a testing laboratory have indicated not only very greatly decreased fuel consumption but also an increase of approximately one-third in the power developed by the motor, the test being made in connection with a popular motor vehicle having an eight cylinder engine. It has been found that the mixture of the gaseous fuel with the incoming relatively cool air does not result in condensation of any of the fuel prior to its entrance into the engine, and accordingly the engine is supplied with a completely gaseous and homogeneous fuel mixture. The only condensation which was found to occur was in the body 38 and particularly in the passage 50. Such difficulty readily was overcome by the simple expedient of heat insulating the body 38.

In the normal operation of the apparatus most of the fuel for idling is supplied through the pipe 89 in the manner stated. When the engine is operating at increased speeds most of the fuel is supplied through the valve opening 68, a relatively small proportion being supplied through the pipe 89. When the engine has stopped, the valve 66 obviously returns to its closed position and the temperature drop in the heating chamber 26 gradually causes the fuel to condense in such chamber. Accordingly some fuel will be in the chamber 26 ready for gasification upon the next starting of the engine, although no initial fuel is needed in view of the foregoing description wherein it was pointed out that initial operation is carried out by the carburetor which is functioning in its normal manner until the chamber 26 is heated. The operation of the valve arm 16 then starts the normal operation of the gas generating means, the fuel being immediately supplied in liquid form to the heating chamber 26 to be converted into gas and supplied to the engine before the fuel is exhausted from the float chamber of the carburetor.

The operation of the form of the invention shown in Figures 4 to 8 inclusive is substantially identical with the operation of the form of the invention described and need not be referred to in detail. Fuel is supplied from the fuel pump to the pipe 116 and thence to the conventional carburetor during the starting and initial running of the engine. The element 114 may be either a thermostatically operated or pressure responsive member, as may be desired, and controls the automatic valve mechanism 112. Upon the increasing of the temperature or the pressure to a given point in the chamber 101, the valve mechanism 112 will disconnect the pipe 115 from the pipe 116 and connect it to the pipe 110 to supply fuel through the jets 109 (Figures 4 and 6). The atomized fuel is thus supplied to the heating chamber 101 into which heat is radiated by the fins 105. The chamber 101 is obviously heated by exhaust gases passing from the engine into the chamber 98 through openings 99. The fuel as it is gasified is supplied to the chamber 123 (Figure 7) under the pressure generated incident to the gasification of the fuel and the pressure control valve 122 functions in

exactly the same manner as the pressure control valve previously described to regulate the flow of gas through the passage 129. The admission of fuel into the chamber 101 need not be controlled by a float valve such as the float valve mechanism shown in Figure 1 but may be controlled in accordance with the pressure in the chamber 101. This pressure, when it builds up to a predetermined point blocks the functioning of the conventional fuel pump and prevents such pump from supplying additional fuel except as pressure drops in the chamber 101. The check valve 115 prevents pressure in the chamber 101 from forcing fuel back through the fuel line 115.

The use of the nozzle 120 for spraying water into the heating chamber is a desirable but not necessary adjunct to the apparatus. As is well known, the admission of some water vapor into the intake manifold of an internal combustion engine assists combustion in the engine and accordingly it is desirable that such means be employed.

The fuel control valve mechanism which controls the flow of fuel from the passage 129 into the engine functions in exactly the same manner as the corresponding elements in the form of the invention previously described and need not be repeated in detail. The position of the diaphragm 138 depends upon relative pressures in the chambers 137 and 154, which pressures, in turn, are dependent upon the area of the bleed passage 157 and the effective area of the passage 159 as determined by the position of the valve 163. With the engine operating at high speed, relatively low pressure will exist in the chamber 144 and consequently in the chamber 158 to open the valve 163 and thus reduce pressure in the chamber 154. Pressure in the chamber 137 will then move the diaphragm 138 to open the valve 140 to the proper extent to admit gas into the chamber 144.

When the motor is idling, greater pressure will exist in the chambers 144 and 145 but a relatively high vacuum will be present in the intake manifold and consequently in the pipe 172. Air will be drawn from the passage 170 to move the diaphragm 159' and open the valve 163 to admit gas through the bleed passage 157, chamber 154, passages 159 and 170 and pipe 172 into the intake manifold. The decreased pressure in the chambers 154 and 158 also results in the opening of the valve 140 to a greater extent than otherwise would occur. Thus idling fuel is supplied through the pipe 172 and through the port 141.

The main adjusting valves 95 (Figure 1) and 151 (Figure 7) are adjustable to determine the rate of exhaustion of gas through the ports which they control and also to determine the rate of exhaustion of air through the passages 85 (Figure 2) and 170 (Figure 7) to determine the degree of vacuum in the chambers with which such passages are connected. Similarly, the idling valves 88 (Figure 2) and 173' (Figure 7) determine the rate of exhaustion of air through the ports which they control, thus determining the rate of flow of fuel into the intake manifold when the engine is idling.

From the foregoing it will be apparent that the present invention contemplates a method of forming fuel charges from volatile liquid fuels wherein fuel is continuously converted into gas which is fed to a body of air moving into an internal combustion engine whereby a completely gaseous and homogeneous fuel charge is formed. The method therefore eliminates the necessity

of depending upon the flow of air into an intake manifold for evaporating atomized volatile liquid fuels, such prior methods failing to provide anything approximating perfect combustion because of the incomplete gasification of the fuel. Because of the extremely small time interval existing between the mixing of the gaseous fuel and the air and the entrance of the fuel mixture into the engine, and because of the normal turbulence occurring in the fuel mixture as it flows to the engine, no condensation of fuel occurs. As stated, therefore, the explosive charge reaches each cylinder in completely gaseous form to be perfectly burned. Such fact permits the supplying of relatively cool unheated air into the intake manifold, thus avoiding expansion of the fuel charge and satisfying the full volumetric requirements of the engine. In actual tests, therefore, the present method and apparatus have been found not only to greatly decrease the rate of fuel consumption of a given engine but also to very materially increase the power developed by the engine.

It is to be understood that the forms of the invention herewith shown and described are to be taken as preferred examples of the same and that various changes in the shape, size and arrangement of parts may be resorted to without departing from the spirit of the invention or the scope of the subjoined claims.

We claim:

1. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a chamber, conduit means for supplying liquid fuel to said chamber, means for converting said fuel into an air-free gas, a duct connecting said chamber to said intake pipe to supply gasified air-free fuel to said pipe to be mixed with air flowing therethrough, means constructed and arranged for controlling the flow of gaseous fuel through said duct into the intake pipe at varying rates depending upon pressure conditions in said intake pipe, and means for directing liquid fuel from said source to said feed pipe or to said conduit means.

2. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a chamber, conduit means for supplying liquid fuel to said chamber, means for converting said fuel into an air free gas, a duct connecting said chamber to said intake pipe to supply air-free gasified fuel to such pipe to be mixed with air flowing therethrough, means constructed and arranged for controlling the flow of gaseous fuel through said duct into such intake pipe at varying rates depending upon pressure conditions in the intake pipe, means constructed and arranged to control the flow of liquid fuel from the fuel source to said chamber at a rate corresponding to the rate of consumption of the fuel by the apparatus, and means for directing

liquid fuel from said source to said feed pipe or to said conduit means.

3. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a closed chamber, conduit means for supplying liquid fuel under pressure to said chamber, means for heating said chamber to convert fuel therein into an air-free gas, a duct connecting said chamber to said intake pipe to supply air-free gasified fuel to such pipe to be admixed with air flowing therethrough, means constructed and arranged for controlling the flow of gaseous fuel through said duct into the intake pipe at varying rates depending upon pressure conditions in said intake pipe, and means for directing liquid fuel from said source to said feed pipe or to said conduit means.

4. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a closed chamber, conduit means for supplying liquid fuel under pressure to said chamber, means for heating said chamber to convert fuel therein into an air-free gas, a duct connecting said chamber to said intake pipe to supply air-free gasified fuel to such pipe to be admixed with air flowing therethrough, means constructed and arranged for controlling the flow of gaseous fuel through said duct into the intake pipe at varying rates depending upon pressure conditions in said intake pipe, means responsive to pressures in said chamber and constructed and arranged to control the flow of liquid fuel from said fuel source to said chamber in accordance with pressures therein, and means for directing liquid fuel from said source to said feed pipe or to said conduit means.

5. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a chamber, conduit means for supplying liquid fuel to said chamber, means for heating said chamber to convert fuel therein into an air-free gas, a duct connecting said chamber to said intake pipe to supply air-free gasified fuel to such pipe to be mixed with air flowing therethrough, a pressure control valve in said duct for controlling the pressure of gas flowing from said chamber, a flow control mechanism in said duct between said pressure control valve and said intake pipe for controlling the flow of gaseous fuel from said duct into the intake pipe at varying rates depending upon pressure conditions in said intake pipe, and means for directing liquid fuel from said source to said feed pipe or to said conduit means.

6. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, a chamber, conduit means for supplying liquid fuel to said chamber, means for heating said chamber to convert fuel therein into an air-free gas, a duct connecting said chamber to said intake pipe to supply air-free gasified fuel to such pipe to be mixed with air flowing therethrough, a pressure control valve in said duct for controlling the pressure of gas flowing from said chamber, a flow control mechanism in said duct between said pressure control valve and said intake pipe for controlling the flow of gaseous fuel from said duct into the intake pipe at varying rates depending upon pressure conditions in said intake pipe, means constructed and arranged for controlling the supply of liquid fuel from the fuel source to said chamber at varying rates in accordance with pressures in said chamber, and means for directing liquid fuel from said source to said feed pipe or to said conduit means.

7. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, and an exhaust conduit for the passage of products of combustion from the apparatus, a chamber substantially surrounded by a portion of said conduit, conduit means for supplying liquid fuel to said chamber to be converted into an air-free gas by the heat of the products of combustion passing through said conduit, a duct connecting said chamber to said intake pipe to supply air-free gasified fuel to such pipe to be mixed with air flowing therethrough, means constructed and arranged for controlling the flow of gaseous fuel through said duct into said intake pipe at vary rates depending upon pressure conditions in said intake pipe, and means for directing liquid fuel from said source to said feed pipe or to said conduit means.

8. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomized fuel from said source, mix the atomized fuel with air to gasify it, and supply the gasified fuel to said intake pipe, and an exhaust conduit for the passage of products of combustion from the apparatus at least partially surrounding said exhaust conduit, a chamber substantially surrounded by a portion of said conduit, conduit means for spraying liquid fuel into said chamber to be converted into gas by the heat of the products of combustion in said conduit, a duct connecting said chamber to said intake pipe to supply air-free gasified fuel to such pipe to be mixed with air flowing therethrough, means for controlling the flow of gas through said duct into said intake

pipe, said last named means comprising a flow control mechanism for controlling the flow of gaseous fuel from said duct into said intake pipe at varying rates, depending upon pressure conditions in said intake pipe, and means for directing liquid fuel from said source to said feed pipe or to said conduit means.

9. In combination with the intake pipe of a gaseous fuel consuming apparatus, in which pipe variations in pressure occur in accordance with fuel demands of the apparatus, a source of volatile normally liquid fuel, and a carburetor having a feed pipe for connection to said source, and connected to said intake pipe to atomize fuel from said source, mix the atomized fuel with air to gasify it, and supply the gasified fuel to said intake pipe, and an exhaust conduit for the passage of products of combustion from the apparatus at least partially surrounding said exhaust conduit, a chamber substantially surrounded by a portion of said conduit, conduit means for spraying liquid fuel into said chamber to be converted into gas by the heat of the products of combustion in said conduit, a duct connecting said chamber to said intake pipe to supply air-free gasified fuel to such pipe to be mixed with air flowing therethrough, means for controlling the flow of gas through said duct into said intake pipe, said last named means comprising a flow control mechanism for controlling the flow of gaseous fuel from said duct into said intake pipe at varying rates, depending upon pressure conditions in said intake pipe, means for controlling the rate of supply of liquid fuel to said chamber in accordance with pressures generated therein, and means for directing liquid fuel from said source to said feed pipe or to said conduit means.

10. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber, conduit means for supplying liquid fuel to said chamber, means for converting fuel in said chamber into an air-free gas, a duct connecting said chamber to the intake pipe to supply gasified fuel to such pipe to be mixed with air flowing therethrough, means constructed and arranged for controlling the flow of gaseous fuel through said duct into the intake pipe at vary rates depending upon pressure conditions in the intake pipe, and means for directing liquid fuel from said source to said feed pipe or to said conduit means.

11. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber, conduit means for supplying liquid fuel to said chamber, means for converting fuel in said chamber into an air-free gas, a duct connecting said chamber to the intake pipe to supply gasified fuel to such pipe to be mixed with air flowing

therethrough, means constructed and arranged for controlling the flow of gaseous fuel through said duct into the intake pipe at varying rates depending upon pressure conditions in the intake pipe, means constructed and arranged to control the flow of liquid fuel from the fuel source to said chamber at a rate corresponding to the rate of consumption of the fuel by the apparatus, and means for directing liquid fuel from said source to said feed pipe or to said conduit means.

12. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a closed chamber, conduit means for supplying liquid fuel under pressure to said chamber, means for heating said chamber to convert fuel therein into an air-free gas, a duct connecting said chamber to the intake pipe to supply gasified fuel to such pipe to be mixed with air flowing therethrough, means constructed and arranged for controlling the flow of gaseous fuel through said duct into the intake pipe at varying rates depending upon pressure conditions in the intake pipe, and means for directing liquid fuel from said source to said feed pipe or to said conduit means.

13. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a closed chamber, conduit means for supplying a liquid fuel under pressure to said chamber, means for heating said chamber to convert fuel therein into an air-free gas, a duct connecting said chamber to the intake pipe to supply gasified fuel to such pipe to be mixed with air flowing therethrough, means constructed and arranged for controlling the flow of gaseous fuel through said duct into the intake pipe at varying rates depending upon pressure conditions in the intake pipe, means responsive to pressures in said chamber and constructed and arranged to control the flow of liquid fuel from the fuel source to said chamber in accordance with pressures therein, and means for directing liquid fuel from said source to said feed pipe or to said conduit means.

14. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber, conduit means for supplying liquid fuel to said chamber, means for heating said chamber to convert fuel therein into an air-free gas, a duct connecting said chamber to the intake pipe to

supply gasified fuel to such pipe to be mixed with air flowing therethrough, a pressure control valve in said duct for controlling the pressure of gas flowing from said chamber, a flow control mechanism in said duct between said pressure control valve and the intake pipe for controlling the flow of gaseous fuel from said duct into the intake pipe at varying rates depending upon pressure conditions in the intake pipe, and means for directing liquid fuel from said source to said feed pipe or to said conduit means.

15. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber, conduit means for supplying liquid fuel to said chamber, means for heating said chamber to convert fuel therein into an air-free gas, a duct connecting said chamber to the intake pipe to supply gasified fuel to such pipe to be mixed with air flowing therethrough, a pressure control valve in said duct for controlling the pressure of gas flowing from said chamber, a flow control mechanism in said duct between said pressure control valve and the intake pipe for controlling the flow of gaseous fuel from said duct into the intake pipe at varying rates depending upon pressure conditions in the intake pipe, means constructed and arranged to control the supply of liquid fuel from said source to said chamber at varying rates in accordance with pressures in said chamber, and means for directing liquid fuel from said source to said feed pipe or to said conduit means.

16. Apparatus for forming fuel charges for a gaseous fuel consuming apparatus having an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a closed chamber, conduit means for supplying liquid fuel to said chamber, means for converting fuel in said chamber into an air-free gas, a duct connecting said chamber to the intake pipe to supply gasified fuel to such pipe to be mixed with air flowing therethrough, means constructed and arranged for controlling the flow of gaseous fuel through said duct into the intake pipe, said last named means comprising a gas control valve for controlling the flow of gas from said duct into the intake pipe, a diaphragm connected to said valve, means for effecting pressure variations on opposite sides of said diaphragm to control the position of said gas control valve and accordingly the rate of flow of gas into the intake pipe in accordance with the demands of the apparatus, and means for directing liquid fuel from said source to said feed pipe or to said conduit means.

17. Apparatus for forming fuel charges for a gaseous fuel consuming apparatus having an intake pipe in which variations in pressure occur in accordance with fuel demands of the apparatus, and wherein a source of volatile normally liquid

fuel is employed, and in which a carburetor has a feed pipe for connection to said source and is connected to said intake pipe to atomize fuel from said source, mix the atomized fuel with air to gasify it, and supply the gasified fuel to said intake pipe, comprising a closed chamber, conduit means for supplying liquid fuel to said chamber, means for converting fuel in said chamber into an air-free gas, a duct connecting said chamber to said intake pipe to supply gasified fuel to such pipe to be mixed with air flowing therethrough, means constructed and arranged for controlling the flow of gaseous fuel through said duct into the intake pipe, said last named means comprising a gas control valve for controlling the flow of gas from said duct into the intake pipe, a diaphragm connected to said valve, means for effecting pressure variations on opposite sides of said diaphragm to control the position of said gas control valve and accordingly the rate of flow of gas into the intake pipe in accordance with the demands of the apparatus, means for controlling the supply of liquid fuel to said chamber in accordance with pressures present therein, and means for directing liquid fuel from said source to said feed pipe or to said conduit means.

18. Apparatus for forming fuel charges for a gaseous fuel consuming apparatus having an exhaust conduit and an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber substantially surrounded by a portion of said exhaust conduit, conduit means for supplying liquid fuel from said source to said chamber to be converted into an air-free gas by the heat of the products of combustion passing through said exhaust conduit, a duct connecting said chamber to the intake pipe to supply gasified fuel to such pipe to be mixed with air flowing therethrough, means constructed and arranged for controlling the flow of gaseous fuel through said duct into the intake pipe at varying rates depending upon pressure conditions in the intake pipe, and means for directing liquid fuel from said source to said feed pipe or to said conduit means.

19. Apparatus for forming fuel charges for a gaseous fuel consuming apparatus having an exhaust conduit and an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber at least partially surrounded by said exhaust conduit, conduit means for supplying liquid fuel from said source to said chamber to be converted into gas by the heat of the exhaust gases in said exhaust conduit, a duct connecting said chamber to the intake pipe to supply gasified fuel to such pipe to be mixed with air flowing therethrough, a pressure control valve in said duct for controlling the pressure of gas flowing from said chamber, a flow control mechanism in said duct between

said pressure control valve and the intake pipe for controlling the flow of gaseous fuel from said duct into the intake pipe at varying rates depending upon pressure conditions in the intake pipe, and means for directing liquid fuel from said source to said feed pipe or to said conduit means.

20. Apparatus for forming fuel charges for a gaseous fuel consuming apparatus having an exhaust conduit and an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber at least partially surrounded by said exhaust conduit, means for spraying liquid fuel into said chamber to be converted into gas by the heat of the products of combustion in said exhaust conduit, a duct connecting said chamber to the intake pipe to supply gasified fuel to such pipe to be mixed with air flowing therethrough, means for controlling the flow of gas through said duct into the intake pipe, said last named means comprising a flow control mechanism for controlling the flow of gaseous fuel from said duct into the intake pipe at varying rates depending upon pressure conditions in the intake pipe, and means for direct-

ing liquid fuel from said source to said feed pipe or to said spraying means.

21. Apparatus for forming fuel charges for a gaseous fuel consuming apparatus having an exhaust conduit and an intake pipe in which variations in pressure occur in accordance with fuel demands of the apparatus, and wherein a source of volatile normally liquid fuel is employed, and in which a carburetor has a feed pipe for connection to said source and is connected to said intake pipe to atomize fuel from said source, mix the atomized fuel with air to gasify it, and supply the gasified fuel to said intake pipe, comprising a chamber at least partially surrounded by said exhaust conduit, means for spraying liquid fuel into said chamber to be converted into gas by the heat of the products of combustion in said exhaust conduit, a duct connecting said chamber to the intake pipe to supply gasified fuel to such pipe to be mixed with air flowing therethrough, means for controlling the flow of gas through said duct into the intake pipe, said last named means comprising a flow control mechanism for controlling the flow of gaseous fuel from said duct into the intake pipe at varying rates depending upon pressure conditions in the intake pipe, means for controlling the rate of supply of liquid fuel to said chamber in accordance with pressures generated therein, and means for directing liquid fuel from said source to said feed pipe or to said fuel spraying means.
